VARIABLE PITCH PROPELLER

William L. Greene, Washington, D. C., assignor to
Engineering and Research Corporation, River-
dale, Md., a corporation of Maryland

Application June 1, 1944, Serial No. 538,248

6 Claims. (Cl. 170—160.21)

1

This invention relates to variable pitch propellers and, more particularly, to those of such propellers which automatically operate to maintain a constant, predetermined engine speed.

It is a principal object of the invention to provide, in a device of the type described, means contained in the propeller assembly and not requiring manual or other control by the pilot, which will cause the propeller to maintain any of one or more predetermined engine speeds. Thus, for certain conditions, such as take-off, it may be desirable to maintain the engine speed at a certain constant value, or within a predetermined range, while for other conditions, such as level flight at high speed, it may be desirable to maintain the engine speed at another constant value or within a range different from the value or range desired for the other condition. This governing of the propeller and engine speed at these values or ranges of speed is provided by the present invention and permits operation at optimum conditions at the speed levels at which the conditions of governing occur.

It is another principal object of the invention to provide pitch-varying means for a variable pitch propeller which will be controlled by the speed of rotation of the propeller and, as a corollary to this object, to provide new and improved means for utilizing the speed of rotation of the propeller to vary the pitch thereof.

A further object of the invention is to provide novel and improved fluid pressure means for adjusting each blade of a single or multi-blade propeller system about its axis in order to vary the pitch thereof.

A further object of the invention is to provide, in a fluid-pressure operated pitch changing system having valve means for controlling the flow of operating fluid to the fluid motor, means which are controlled by the speed of rotation of the propeller for operating the valve means to so regulate the flow of fluid to the motor as to cause the pitch of the propeller to be adjusted in accordance with the speed of rotation of the propeller.

Another object of the invention is to provide means in a fluid-pressure operated pitch-varying system for limiting the increase or decrease of pitch to predetermined values.

Other objects and features of novelty of the invention will be made apparent by the following description and the annexed drawings the disclosure of which, it will be understood, is only illustrative of the invention and imposes no limitation thereon not imposed by the appended claims.

Referring to the drawings, in which similar reference characters refer to like parts,

Fig. 1 is a sectional view through a propeller, hub and shaft assembly including pitch chang-

ing means and a control therefor, all according to the invention;

Fig. 2 is a view on a reduced scale taken on line 2—2 of Fig. 1;

Fig. 3 is a view of parts shown in Fig. 1 and illustrating the valve position, at high speed, to increase the pitch;

Fig. 4 is a view similar to Fig. 3 illustrating the valve in blanking position after the control means have assumed a state of equilibrium;

Fig. 5 is a view of parts shown in Fig. 1 illustrating the operation of the means which permit constant speed maintenance at a level different from that effected during operation as illustrated in Fig. 3;

Fig. 6 is a graphic illustration of the movement of the valve in arriving at a position in which constant propeller speed is maintained, and

Fig. 7 is a partly diagrammatic view showing an embodiment of the invention having means for effecting constant speed maintenance at a plurality of levels.

In the drawings there is disclosed a preferred form of the invention which comprises the drive shaft 2 to the end of which is attached a cylindrical hub 4 in the opposite open ends of which are arranged two plates 6, 8, which are held from inward movement by flanges 10 extending radially inwardly from the wall of the hub 4, and which are held from outward movement by rings 12 which are threadedly attached within the opposite open ends of the hub and are separated from the plates 6, 8 by ball bearings 14 whereby the plates are freely rotatable. A propeller blade 16 is attached to each of the plates 6, 8 by threaded bolts 18 and extends therefrom radially of the shaft 2. It will be obvious that rotation of the shaft 2 will cause rotation of the blade system in the usual manner of a propeller, and that each blade and its attached plate 6 or 8 may be rotated about the axis thereof in order to effect pitch variation.

Means are provided by the invention for changing the pitch of the blades 6, 8 and such means comprise a movable cylinder 20 which is disposed within the hub 4 with its axis at right angles to the axis of the hub and of the blades and parallel to the axis of the drive shaft 2. The cylinder surrounds a fixed disc or piston 22 which is attached at its center to a tube 24 which extends forwardly from the center of a plate 26 which is attached to the hub 4 and which closes the forward end of the hollow crankshaft shaft 2, forming therein a chamber 28 which is supplied with the normal engine lubricant which is already under pressure, through a restricted port 30 which extends through the wall of the crankshaft and through a bearing 32 therefor. The cylinder 20 is provided exteriorly with oppositely-extending ears 34 which are respectively connect-

ed, by pins 35 to the adjacent plates 6, 8 eccentrically thereof. The cylinder is slidably longitudinally of the tube 24 and with respect to the fixed disc or piston 22 and it will be apparent that if fluid under pressure is supplied to one or the other side of the piston the cylinder will be moved, with respect to the piston, thereby causing the plates 6, 8 and the blades 16 which are attached thereto to be moved about the axis of the respective blades to vary the pitch thereof.

Means are provided by the invention for introducing fluid to one or the other side of the piston 22 within the cylinder 20 and exhausting it from the other side in order to cause a corresponding movement of the cylinder. Such means comprise, broadly, a system of ports connecting the various parts of the system to a valve chamber, and valve means within the chamber for distributing the pressure fluid. The valve chamber is formed by a passage 55 which extends longitudinally and centrally of the tube 24. The valve means comprises a stem 56 which is slidably mounted within the passage 55 and has spaced, reduced diameter parts 58, 60, 62 which are separated by spaced enlarged parts 64, 66, 68 which are of the same diameter as the inside of the passage 55 and as the main part of the valve stem, thus providing three separated, annular chambers 70, 72, 74 between the three reduced-diameter parts of the valve stem and the inner wall of passage 54. The rearward part of the axial passage 55 through tube 24 communicates with the exhaust passage 40.

The port system comprises a high pressure inlet port 80 which extends longitudinally through the wall of tube 24 exteriorly of passage 55 and communicates as its one end with the high pressure reservoir 28 and at its other end with the interior of the reduced-diameter passage 55 through the central port 82 of three ports, which central port is disposed at about the middle of the piston 22. The forward port 84 of the three ports connects the interior of the valve chamber 55 to the interior of cylinder 20 at the forward side of piston 22, while the rearward port 86 of the three ports connects the valve chamber 54 with the interior of the cylinder at the rearward side of the piston. The three ports 82, 84, 86 are preferably aligned longitudinally of the tube 24. In another part of tube 24 there is formed a longitudinally-extending passage 90 which communicates at its rear end with the exhaust passage 40 and at its forward end with the valve chamber 55 through two spaced ports 92, 94 which are respectively positioned just outwardly of the two ports 84, 86.

The spacing of the parts of the port and valve systems and the range of movement of the valve are such that when the valve stem 56 is in such position that the central or high-pressure port 82 is communicated through annular chamber 70 or 72 with cylinder inlet passage 84 or 86, the other cylinder inlet passage will be connected to exhaust port 92 or 94 through one of the annular chambers formed by the reduced-diameter parts of the valve stem. Thus, when the valve stem is in the position shown in Fig. 1 high pressure fluid flows from reservoir 28, through passage 80, port 82, annular chamber 72 and port 86 to the cylinder 20 on the right-hand or rearward side of piston 22. At the same time the left-hand or forward side of the cylinder will be connected to exhaust passage 40 through port 84, annular chamber 70, port 92, and passage 90. The cylinder will therefore be moved to the right (or rearwardly) and in the preferred mode of operation of the invention such

movement of the cylinder will cause reduction of pitch of the blades.

If the valve stem is moved to the right from the position shown in Fig. 1 to that shown in Fig. 5 the high-pressure supply port 82 communicates with the cylinder inlet port 84, but is blanked off from cylinder inlet port 86. At the same time, outlet port 92 is blanked by the enlarged part of valve stem 56, and outlet port 94 is communicated to cylinder port 86 through annular chamber 70. Thus, fluid under pressure flows to the cylinder at the left-hand or forward side of the piston and is exhausted from the right-hand or rearward side, thereby causing the cylinder to move forwardly or to the left as viewed in Fig. 6 and, in the preferred embodiment of the invention, causing pitch-increasing movement of the propeller blades.

In the valve position shown in Fig. 4 the enlarged part 64 of the valve stem blanks off the high pressure inlet port 82, while the valve rod 56 and the enlarged part 66 blank off the outlet ports 92 and 94. In this condition flow of fluid to or from the cylinder chambers is stopped and the cylinder is maintained in its position at the time the valve reached the blanking position. This position is assumed by the valve when the valve control means, which are described hereinafter, reach a condition of equilibrium such as is shown in Fig. 4.

Means are provided by the invention for operating the valve means in accordance with the speed of rotation of the propeller and such means comprise centrifugally-operated devices which move the valve means in one direction as the speed of rotation increases, and spring means which constantly urge the valve in the opposite direction. In the disclosed embodiment a cylindrical housing 100 is threadedly connected to the forward wall of the hub 4 and on spaced parts of the interior wall thereof are pivotally mounted one or more centrifugally-operated devices 102. Each of these devices comprises two integrally united angularly-related arms 104, 106 which extend in different directions from the pivotal support of the centrifugal device of which they form a part. Each arm 104 is so positioned that it engages the forward face of a collar or abutment member 108 which is screw-threaded to the forward end of the valve rod 56. Each arm 106 is so positioned that it may freely move under the action of centrifugal force, thereby moving arms 104 and causing the valve rod to be moved in accordance with changes in centrifugal force and therefore in response to changes in the speed of rotation of the propeller system. A compression spring 110 bears at its one end on the rearward part of the collar 108 and at its other end on the forward end of a two-part device 112 which is threadedly connected to the forward end of the tube 24, and the spring therefore constantly urges the collar 108 and the valve rod in a forward direction, resisting the effort of the devices 102 under the action of centrifugal force to move the valve rod to the rear.

The parts are so constructed and arranged that when the speed of rotation of the propeller system reaches a pre-determined level the centrifugally-operated means will move the valve rod in pitch-increasing direction, i. e. to the right as shown in the drawings, against the force of spring 110, while the spring will maintain the valve parts in their left-hand, or pitch-decreasing position, as shown in Fig. 1 of the drawings so long as the centrifugal effort of the arms 106 is less than the force of the spring means.

Means are provided by the invention for ad-

justably limiting the pitch-decreasing movement of the parts. Such means comprise a tubular member 120 connected concentrically to the forward end of the cylinder 20 and extending forwardly therefrom and a second tubular member 122 extending rearwardly from the hub-carried tubular member 100 and surrounding and being concentric with the member 120. The relatively fixed member 122 has an inturned flange 124 on its rearward end which is in the path of and engageable by a radial flange 126 which extends outwardly from the wall of member 120. The member 122 is preferably screw-threaded at its forward end to the member 100 in order that the position of the abutment or stop 124 may be changed. It will be seen that pitch-decreasing movement of the cylinder, i. e. to the right as shown in the drawings, will be positively stopped at a pre-determined point by engagement of the flange 126 with flange 124. Pitch-increasing movement of the cylinder, i. e. to the left as shown in the drawings, will be stopped by an abutment 127 extending inwardly from the inner wall of tube 122 adjacent the forward end thereof. The limit stops 124, 127 are provided principally to prevent over-travel of the cylinder due to any possible failure of the parts or improper functioning. Ordinarily the control mechanism described herein prevents improper operation.

The operation of the described parts as a speed-governing means will now be described, reference being made to the curve of Fig. 6 as well as to the other figures. When the aircraft is on the ground and the propeller is idling the centrifugal force exerted by arms 106 is less than the force of the opposing spring means 110 and the spring means therefore hold the valve means in the position shown in Fig. 1, in which the cylinder 20 is moved to its most extended position in a pitch-decreasing direction, being held from further movement by the stop means 124, 126. The condition of the system at this time is represented by point A on the curve of Fig. 6, at which the air-speed is zero and the pitch-angle is a minimum. As the aircraft moves forward to take off, the centrifugal force on devices 102 does not increase sufficiently to overcome the action of spring 110 and the valve parts are held in the minimum-pitch position during this period. As the aircraft approaches level flight conditions the power theretofore utilized in take-off and climbing is translated into increased propeller speed and the action of centrifugal force on devices 102 begins to overcome the effort of the spring 110, causing the valve means to so move that eventually, as shown at point B, the pitch-changing means are caused to move in pitch-increasing direction, i.e. the cylinder 20 moves to the left as shown in the drawings. The positions of the parts at the beginning of this movement are illustrated in Fig. 3, when the force of the compressed spring becomes greater than the centrifugal force acting on devices 102, the the valve parts will be moved to the left, causing the cylinder 20 to move to the right to decrease the pitch of the blades. Such decreased pitch will cause the speed of rotation to be increased, in accordance with well-known laws, and the force of the centrifugal devices 102 will again overcome that of spring 110, moving the valve parts to pitch-increasing position, from which the parts will be moved to pitch-increasing position, and so on. Each successive pitch-increasing or pitch-decreasing movement will be of

a shorter duration than the preceding one, whereby the system will finally reach a stable condition as shown at point D in Fig. 5 which will be a pitch condition, i. e. a position of cylinder 20, 5 which will be optimum for the speed of rotation of the propeller system and therefore for the existing air speed. Only a very short period of time, for example a few seconds, will be required for this stable condition of pitch to be reached 10 after a stable flight condition is achieved. The position of the parts at this time is illustrated in Fig. 4, in which it will be seen that the flow of fluid to or from either side of the piston is 15 shut off, thereby holding the propeller from further pitch-changing movement so long as the existing condition of flight remain unchanged. The centrifugal devices 102 and spring 110 are now in a state of equilibrium.

The described system will operate as a speed 20 governor for the propeller system as a pre-determined speed, for example 2000 R. P. M., which is selectable by proper design and proportioning of the spring 110 and the centrifugal devices 102. After the propeller system reaches a stable 25 condition at this speed, any variation from such range will cause one or the other of the forces in equilibrium, i. e. the spring and the centrifugal devices, to overcome the other, thereby increasing or decreasing the pitch and decreasing or increasing the speed of rotation of the system to the pre-determined range. For example, assume 30 that the aircraft is in level flight and the rotary speed of the propeller is at the prescribed level. If the aircraft now begins to climb, the rotary 35 speed will decrease because the decrease in forward speed of the aircraft causes a heavier load on the blades, the centrifugal force acting on devices 102 will decrease, and the spring 110 will move the valve parts to the left from their position as shown in Fig. 3, causing the pitch to be 40 decreased and thereby increasing the speed. The speed will not increase above the prescribed 45 range as the centrifugally-operated devices will move the valve parts to pitch-increasing (speed decreasing) condition before the upper speed limit is reached.

Means are provided by the invention for causing the pitch-controlling system to govern the speed of rotation of the propeller system at two 50 or more speeds. The system heretofore described will operate to maintain a constant speed of rotation at one level, for example 2000 R. P. M., while that to be described hereinafter will maintain constant speed at another level, for example 55 at 2500 R. P. M. The means for effecting this comprise, generally, means for changing the force exerted by the compression spring 110 but might, with equal effect, comprise means for changing the force exerted by the centrifugal 60 devices 102 at a given speed. In the disclosed embodiment of the invention such means comprise the two-part abutment 112 against which the rear end of spring 110 bears, and which comprises a rear part 150 having a cylindrical part 152 interiorly screw-threaded to the exterior of tube 24 and a radially extending flange 154. The abutment 112 also includes a forward member 156 having a cylindrical part 158 which slidably 65 surrounds the cylindrical part 152 of the member 150, and also has a radially-extending flange 159 against which the rear end of spring 110 bears and which is constructed and adapted to be normally pressed by the spring into face-to-face 70 engagement with the flange 154. The inner surfaces of the outer peripheral parts of the flanges 75

154, 158 are inclined toward each other to form a straight-sided ball race receiving the balls 160. The abutment 112 is within the cylindrical extension 120 on the forward end of cylinder 20 and the flanges 154, 158 are so constructed and proportioned that the balls 160, which are between such flanges are held by the cylindrical extension 120 in an inner position, as shown in Figs. 1 and 3, in which the flanges are held apart, the flange 158 being moved from the flange 154 against the force of spring 110.

The inner wall of the cylindrical extension 120 has an annular groove 180 of substantial axial extent formed therein. This groove is spaced from the forward end of the member 120 and so long as the balls 160 engage the surface between such end and the groove they will hold the flanges 154, 158 apart in the described manner. Sufficient leftward, or pitch-increasing, movement of the cylinder 20 will cause the balls to move into the groove, being urged to do so by the force of spring 110 transmitted through the ball race of flange 158. When this occurs, the balls will no longer hold the flanges apart and spring 110 will move apart 150 to the right until the flanges abut, the parts arriving in the positions shown in Fig. 4. In this operation the length of the compression spring 110 is increased and its effect vis-a-vis the centrifugally-operated parts 102 will be changed and a condition of equilibrium between them can therefore only be achieved under conditions (e. g. at a different speed) different from those which obtained while the balls were out of the groove 180. The pitch-varying system will therefore act to maintain a constant speed at a new level which will be determined by the distance of the forward edge of the groove from the position occupied by the balls when governing at the lower constant speed range.

For each range of forward speeds of the aircraft there will be an optimum rotary speed of the propeller which may be pre-selected by varying the spring tension by the means described, which may be effected one or more times throughout the total range of forward speeds. This variation of the spring tension is accomplished by the pitch changing movements of the propeller system as it accommodates itself to changes in forward speed and thereby moves the tube 120. There may, of course, be more than the two pre-selected spring tensions described. The position and extent of each governor setting will be determined by the requirements of each aircraft installation. For example, the propeller system of an airplane having a maximum speed of 200 M. P. H. might be provided with a tube 120 such as is disclosed in Fig. 7. This sleeve is designed to cause governing to 2100 R. P. M. (maximum engine rated power) from the propeller pitch condition corresponding to 0 M. P. H. to 100 M. P. H., to cause governing to 1800 R. P. M. (cruising power) from the propeller pitch corresponding to 100 M. P. H. to 175, M. P. H., and to cause governing to 2100 R. P. M. from the propeller pitch corresponding to 175 to 200 M. P. H. (high speed).

The effect of the described apparatus is illustrated by the dotted line in Fig. 6. As the force exerted by spring 110 is decreased when the balls move into the groove, the pitch-changing means (cylinder 20) must move farther in a pitch-increasing direction than before in order to overcome the action of centrifugal force on the valve means, and the weaker condition of the spring

causes the centrifugally-operated means to overcome its resistance before such occurrence while the balls are not in the groove.

It is believed that the operation of the invention will be more clearly understood by a consideration of the condition of the various parts at various flying conditions, as shown in the following table:

- (1) Aircraft on ground, no forward movement.
    - a. Centrifugal devices as in Fig. 1.
    - b. Spring holds valve as in Fig. 1.
    - c. Pressure fluid flows to rear of piston.
    - d. Cylinder at rear limit of movement.
    - e. Pitch at minimum.
  - (2) Takeoff. All conditions same as when aircraft is on ground.
  - (3) Level flight at first controlled speed.
    - a. Propeller tends to over speed. Valve means moved to the position shown in Fig. 3. Propeller increases pitch. Rotational speed decreases.
    - b. Centrifugal devices and spring means just balancing each other.
    - c. Valve held in blanked position in which no fluid flows to or from either side of cylinder.
    - d. Cylinder in optimum position for speed.
    - e. Pitch at optimum condition for speed.
  - (4) Speed of aircraft continues to increase.
    - a. Centrifugal devices overcome spring.
    - b. Valve means moved by centrifugal means to position shown in Fig. 3.
    - c. Cylinder moves forwardly to increase pitch, this results in reduction of speed, causing spring to overcome centrifugal devices and move valve to decrease pitch thus increasing speed, etc. etc., until condition of equilibrium is reached.
  - (5) Level flight at second controlled speed. This occurs when pitch has increased to an amount corresponding to a predetermined forward speed and groove 180 has come opposite balls 160 causing the spring load to change to the second governing load.
- All conditions same as level flight at first controlled speed.
- While I have described and illustrated one form which my invention may take it will be apparent to those skilled in the art that other embodiments, as well as modifications of that disclosed, may be made without departing in any way from the scope of the invention, for the limits of which reference must be made to the appended claims.
- I claim:
1. A variable pitch propeller comprising a hub, blades journaled in the hub for pitch-changing movement about their respective axes, fluid pressure operated means connected to the blades and movable in either of two directions to effect pitch-increasing or pitch-decreasing movement thereof, a two-part bearing carried by said fluid pressure operated means, means for holding the two parts of the bearing apart, valve means movable to either of two positions to cause pitch-increasing or pitch-decreasing movement of the fluid pressure operated means and to a third position to prevent movement of the fluid pressure operated means, means responsive to the speed of rotation of the hub and operable by increases in the speed of rotation to move the valve means to cause pitch-increasing movement of the fluid

pressure operated means, a compression spring bearing at one end on the valve means and constantly opposing movement of the valve means caused by the speed-responsive means when acted on by increases in speed and bearing at its other end against one part of said two-part bearing, means operated by a predetermined amount of pitch-increasing movement of the fluid pressure operated means to release the means holding said two parts apart to thereby change the length of the spring and the force exerted thereby.

2. A variable pitch propeller comprising a hub, blades journaled in the hub for pitch-changing movement about their respective axes, fluid pressure operated means connected to the blades and movable in either of two directions to effect pitch-increasing or pitch-decreasing movement thereof, a two-part bearing carried by said fluid pressure operated means, valve means movable to either of two positions to cause pitch-increasing or pitch-decreasing movement of the fluid pressure operated means and to a third position to prevent movement of the fluid pressure operated means, means responsive to the speed of rotation of the hub and operable by increases in the speed of rotation to move the valve means to cause pitch-increasing movement of the fluid pressure operated means, a compression spring bearing at one end on the valve means and constantly opposing movement of the valve means caused by the speed-responsive means when acted on by increases in speed and bearing at its other end against one part of said two-part bearing, a plurality of balls between the two parts of the bearing, a cylindrical member carried by the fluid pressure operated means and having an inner surface surrounding the two-part bearing and normally holding the balls between said two parts against the force of said compression spring, said inner surface having an annular groove therein into which said balls escape when the groove is aligned with the balls to thereby cause the two parts of the bearing to be brought together to thereby increase the length of the spring and reduce the force exerted thereby.

3. A variable pitch propeller mechanism comprising a hub, blades journaled in the hub for pitch-changing movement about their respective axes, means connected to the blades and movable in either of two directions to increase or decrease the pitch of the blades, means responsive to the speed of rotation of the propeller for controlling the operation of the blade-moving means, means exerting a force on said controlling means in opposition to that exerted thereon by increases in the speed of rotation of the speed-responsive means and the force of which is constant over a predetermined range of pitch variation whereby the opposing forces of said means maintain a predetermined pitch and constant speed of rotation, and means including a part which is connected to the blade-moving means and is movable therewith, said means being operable upon movement of said blade-moving means in changing the pitch of the blades to an angle outside of such range to change the force of said opposing means whereby the opposing forces of said means maintain a predetermined speed of rotation different from the first.

4. A variable pitch propeller comprising a hub, blades journaled in the hub for pitch-changing movement about their respective axes, fluid pressure operated means connected to the blades and movable in either of two directions to effect pitch-increasing or pitch-decreasing movement thereof,

valve means movable to either of two positions to cause pitch-increasing or pitch-decreasing movement of the fluid pressure operated means and to a third position to prevent movement of the fluid pressure operated means, means responsive to the speed of rotation of the hub and operable by increases in the speed of rotation to move the valve means to cause pitch-increasing movement of the fluid pressure operated means, spring means constantly urging the valve means to a position causing pitch-decreasing movement of the fluid-pressure operated means, means operable over a predetermined range of pitch variation to maintain substantially constant the force of said spring means whereby the opposing forces of said speed-responsive means and said spring means are balanced at one level to maintain a predetermined constant speed of rotation, and means including a part which is connected to the blade-moving means and is movable therewith, said means being operable upon movement of said blade-moving means in changing the pitch of the blades to an angle outside of said predetermined range to change the force of said spring means whereby the opposing forces of the speed-responsive means and the spring means are balanced at a second level to maintain a predetermined speed of rotation different from the first.

5. A constant speed variable pitch propeller mechanism comprising a hub, blades journaled in the hub for pitch-changing movement about their respective axes, means connected to the blades and movable in either of two directions to effect pitch-increasing or pitch-decreasing movement thereof, means operable in response to the opposing forces of opposing means having an equilibrium point to cause pitch-increasing or pitch-decreasing movement of the blade-moving means as one or the other force exceeds the other, means operable during a predetermined range of pitch variation to maintain constant the force of one of said means whereby the opposing forces of said means are balanced at one level to maintain a predetermined constant speed of rotation, and means operable upon pitch change to successive ranges of values outside said first range to progressively change the force of said one means to successive predetermined values for each of said successive ranges whereby the opposing forces of said means are balanced at a series of levels to maintain a series of predetermined speeds of rotation each different from the others.

6. A variable pitch propeller mechanism comprising a hub, blades journaled in the hub for pitch-changing movement about their respective axes, fluid pressure operated means connected to the blades and movable in either of two directions to effect pitch-increasing or pitch-decreasing movement thereof, a two-part bearing carried by a fixed part of said mechanism, valve means movable to either of two positions to cause pitch-increasing or pitch-decreasing movement of the fluid pressure operated means and to a third position to prevent movement of the fluid pressure operated means, means responsive to the speed of rotation of the hub and operable by increases in the speed of rotation to move the valve means to cause pitch-increasing movement of the fluid pressure operated means, a compression spring bearing at one end on the valve means and constantly opposing movement of the valve means caused by the speed-responsive means when acted on by increases in speed and bearing at its other end against one part of said two-part

bearing; a plurality of balls between the two parts of the bearing, a cylindrical member carried by the fluid pressure operated means and having an inner surface surrounding the two-part bearing and normally holding the balls between said two parts against the force of said compression spring, said inner surface having a plurality of axially spaced annular grooves of different diameters therein into any one of which said balls are released when the groove is aligned with the balls to thereby cause the two parts of the bearing to be brought together by an amount determined by the depth of the groove and the extent of release of the balls, to thereby increase the length of the spring and reduce the force exerted thereby.
